(57) **CLAIM**

The ornamental design for a cell counter display screen with graphical user interface, as shown and described.

DESCRIPTION

FIG. 1 is a view of a first embodiment of a cell counter display screen with graphical user interface of our new design.

FIG. 2 is a view of a second embodiment of a cell counter display screen with graphical user interface of our new design.

FIG. 3 is a view of a third embodiment of a cell counter display screen with graphical user interface of our new design.

FIG. 4 is a view of a fourth embodiment of a cell counter display screen with graphical user interface of our new design.

FIG. 5 is a view of a fifth embodiment of a cell counter display screen with graphical user interface of our new design; and,

FIG. 6 is a view of a sixth embodiment of a cell counter display screen with graphical user interface of our new design.

The portions of the features depicted in broken lines are not part of the claimed design.

1 Claim, 6 Drawing Sheets
